UNITED STATES PATENT OFFICE.

LAWRENCE D. SHINN AND ARTHUR T. SHINN, OF WASHINGTON, DISTRICT OF COLUMBIA.

MEANS FOR PRACTICING GOLF.

Application filed April 4, 1928. Serial No. 267,294.

An object of the invention is to produce a device suitable for practicing the use of iron and wooden golf clubs indoors, or within a restricted area. Another object is to construct a device which will not injure the surface on which it is used, such as a wooden or carpeted floor. Another object is to construct a device which costs little to manufacture and which is not liable to get out of order. Another object is to produce a device for the indoor practice of golf which requires a minimum of space in use. Another object is to construct a device for teaching the indoor practice of golf which consists of a ball attached to a plurality of graduated weights, which progressively retard the flight of the ball and bring the same to rest after it has been struck by a striking implement, such as a golf club. Other objects will appear hereinafter.

Figure 1 is a side elevation of our invention, without the protective covering, and on a reduced scale.

Figure 2 is a detailed plan view of our invention, partly in section, and on a reduced scale.

Figure 3 is an enlarged detailed view, partly in section.

Our invention broadly consists of a captive ball secured by a flexible connection to a flexible system of graduated weights, to the end that the flight of the ball, after being struck by the club will be progressively retarded and finally brought to rest, within a few feet from where it has been struck. Preferably attached to the system of graduated weights is a captive tee. The whole assemblage provides an apparatus whereby the practice of golf with both wooden and iron clubs may be obtained within any ordinary room, or in fact, any place where there is room to swing the clubs.

Referring to the drawings, the numeral 1 indicates a captive ball which may be constructed of material now used in the construction of golf balls, or it may be made of wood, cotton, or solid or hollow rubber. Attached to the ball 1 is a flexible connection 2. The numeral 3 indicates a tee of any preferred construction, which has attached to it a flexible connection 4. There is provided a flexible member 5, to which are fixed by any suitable means a plurality of graduated weights indicated by the numerals 7, 8 and 9. On one end of the flexible

member 5 is attached a loop or eye 6, to which are attached the other ends of the members 2 and 4. The weights 7, 8 and 9 are enclosed in a covering 10 to prevent damage to carpets or furniture and to deaden the noise occasioned during the practice of the device. The shape of the covering 10 is such that it is larger at one end and gradually becomes smaller at the other end, so as to snugly enclose the graduated weights. Means 11 are provided for closing the smaller end of the covering 10. Similar means, not shown, may be provided at the other end of said member 10. The covering 10 may be constructed of any suitable flexible material, such as leather or cloth. The flexible connections 2 and 4 and the flexible member 5 may be constructed of cord, chain or wire, or other material. Although we prefer to attach the tee 3 to the eye 6, such connection is not necessary, and the tee may be used unattached to the weights or ball.

We have found in practice that after the ball is struck, it first picks up the first weight and then, within a few inches more of flight, picks up the second and the others in series, until finally the progressive retardation of the weights will bring the ball to rest within a few feet from where it has been struck. We have found that there is very little danger of any of the connections becoming broken, even after long use, due to the fact that the ball, after first being struck and when it is moving at its fastest, picks up the lightest weight first and the number and size of the weights gradually increases as the flight continues, until its flight is arrested. In the drawings we have shown the weights being made of 3 series, but any suitable number may be employed, the members 7 being of equal weight, the members 8 being of slightly greater weight and the members 9 being of yet greater weight. However, we may employ a series of weights, each of which is a little heavier than its preceding weight. The weights may be strung on the flexible member or may be attached to it by any suitable means.

It is to be understood that the drawings and description herewith have been given merely for illustrative purposes and we desire to be limited only to the extent indicated by the appended claims.

What we desire to secure by Letters Patent is:

1. A device for practicing golf, consisting of a ball, a flexible connection having one of its ends attached to said ball and its other end connected to a plurality of graduated weights.
2. A device for practicing golf, consisting of a ball, a plurality of graduated weights, a flexible connection, means for connecting one end of said flexible connection to said ball and means for connecting its other end to a plurality of graduated weights, and a covering for said weights.
3. In a device of the class described, a ball, a plurality of differential weights, a tee and flexible means for connecting said parts.
4. In a device of the class described, the combination of a ball, a plurality of graduated weight members and means for flexibly

connecting said members with each other, means for connecting the ball with the weight connecting means and a tee having a flexible device joined to the last named connection.

5. In a device of the class described, a ball, a flexible member, a plurality of differential weights attached to said flexible member, said flexible member having means for spacing said differential weights from each other, and a flexible connection having its terminals connected with said ball and weights.

In testimony whereof we have hereunto set our hands this 2nd day of April A. D. 1928.

LAWRENCE D. SHINN.
ARTHUR T. SHINN.
